RENÉ RIBEROLLES, OF PARIS, FRANCE

AIMING APPARATUS FOR ANTIAIRCRAFT FIRE

Application filed June 1, 1931, Serial No. 541,317, and in France June 7, 1930.

In firing against aerial objectives such as aeroplanes peculiar difficulties arise owing to the rapid displacement of the objective in front of the gun.

- 5 It is necessary in fact in firing on such objectives to effect not only the intersection of the trajectories of the objective and of the projectile but also the arrival at the same instant of the objective and of the projectile
10 at the point of intersection of the trajectories.

The present invention relates to an apparatus which overcomes the above mentioned difficulty.

An aiming apparatus according to the invention is illustrated by way of example on the accompanying drawings, in which:—

Fig. 1 is a diagram showing the principle of the aiming apparatus according to the invention.

20 Fig. 2 illustrates a contrivance for determining a length proportional to the distance of the objective from the piece.

Fig. 3 is a section showing the details of the aiming apparatus according to the invention.

Fig. 4 is a view of the entire aiming apparatus mounted on an anti-aircraft gun.

Fig. 5 is a fragmentary longitudinal section of the telescope mounting along the axis 25 AA thereof.

The principle of the apparatus according to the invention is illustrated by Fig. 1. P is the fire arm, P_1 a lateral observation post, Ao the position of the objective at the departure of the projectile, and A its position on the arrival of the projectile.

AoA is assumed to be straight, V being the velocity of the objective, assumed to be constant along the path AoA , t being the time taken by the projectile to go from P to A, l finally being the distance from P to P_1 , it is evident that:

$$AoA = Vt$$

45 If a line parallel to AoA is taken through P, and on this parallel line, starting from the point A a distance

$$PB = \frac{t}{D}$$

50

is produced, and if through the point B obtained a parallel line to AoA is taken which cuts PA at a point C, the two triangles $PAoA$ and PBC obtained are similar, the following proportion is deduced:

$$\frac{PC}{PA} = \frac{PB}{AAo}$$

or

$$PC = PA \times \frac{PB}{AAo}$$

or, if PA , PB , AAo are replaced by their value as a function of VtD :

$$PC = D \times \frac{t}{D} = \frac{1}{V}$$

Moreover, the ratio of the triangles is:

$$\frac{PC}{PA} = \frac{1}{V} = \frac{1}{VD}$$

It is thus seen that if at CPB is reproduced a triangle similar to the spatial triangle $PAoA$ on the scale $\frac{1}{VD}$, the sides PB and PC have the values indicated above and that if the side BC is materialized by a rod bearing a telescopic sight directed on the objective, the side PC will represent the direction to be given to the gun in order to be aimed at the position of the objective on the arrival of the projectile.

In order to reproduce this triangle, it is necessary that the side PB of the triangle be made equal to $\frac{t}{D}$ and directed parallel to the path of the objective and that the length of the side PC be made equal to $\frac{1}{V}$.

The choice of the scale $\frac{1}{VD}$ of reproduction of the spatial triangle formed by the gun, the position of the objective at the departure of the projectile and its position at the arrival of the projectile, is one of the characteristic principles of the invention.

The object thereof is to arrange that the

100

- sole variable side of the triangle to be constructed is the side PB which is the smallest side of the triangle and the movement of which reduces itself to a rotation in a plane.
- 5 This arrangement permits the length of the side PB to be obtained with a cam of very small dimensions, actuated in altitude h and in site s , being granted that:

$$0 \quad \frac{t}{D} = f(h, s)$$

f being a function dependent on the ballistic conditions of the fire.

- Being granted the scale which it is necessary to choose for the reproduction of the triangle PBC, in order to obtain the desired precision, it is easy to see that if it is desired to obtain in an analogous manner the length of the other sides of the triangle PBC which 5 may attain as much as approximately ten times the length of the side PB, a cam of practically unobtainable dimensions would be required. Moreover, as the other sides could take all directions in space, the transmission of movement would be rendered extremely difficult.

These remarks emphasize the vital importance of the choice of the scale $\frac{1}{VD}$.

- 0 The length of the side PC will be made equal to $\frac{1}{V}$ by means of a simple graduation in velocity, the processes employed to ascertain this speed being outside the present invention.

This side of the triangle will be constituted by an arm pivoted about a horizontal axis fast with the displacement in site of the gun and constantly parallel with this latter.

- 0 At the point C will be provided an eye or the equivalent. The rod BC will be fixed at B and will be capable of sliding at C through the eye.

- At the point B, the joint will be constituted by a support with a vertical axis, carrying a horizontal axis to which will be fixed the rod BC and the telescope.

- By this means, the rotations of the telescope about these axes, during the movement of the apparatus will register the azimuth and the site of the position A_o of the objective at the departure of the projectile.

- To summarize, if on the above described apparatus is registered the altitude, the velocity and the direction of the target, and if, by actuating the controls of the gun (that is to say also of the arm PC) the telescope (that is to say the side BC) is aimed at the objective, the arm PC (that is to say the gun) will 30 be found to be directed towards the position which the objective will occupy at the arrival of the projectile.

- The arrangement which has just been described can also be used to correct parallaxes 35 in the case of a lateral observation.

In fact if the triangle P₁P₁A (Fig. 1) is reproduced on the scale $\frac{1}{(11)D}$, the advantages are the same as those explained above in regard to the scale $\frac{1}{VD}$ of the triangle PBC. 70

P B¹ C¹ being this triangle:

Its sides have the value:

$$PC^1 = \frac{1}{(11)}$$

$$PB^1 = \frac{1}{D}$$

If therefore the side B¹C¹ is rendered parallel to the direction P₁A of the objective, seen from the central post, the side PC¹ (that is to say the gun) will be directed on the target. 80

In order to render the sides B¹C¹ and P₁A parallel it suffices to transmit to the telescope from the gun, directed along B¹C¹, the site and azimuth found at the central post P₁. 85

Inversely, if these latter elements are transmitted to the gun (that is to say to the side P C¹), the telescope (that is to say the side B¹C¹) will be found directed on the target. 90

In order that the reconstitution of the triangle may be complete, it will suffice to give the side PC¹ the length $\frac{1}{1}$ by means of a 95 graduation, to direct the vector PB¹ once for all along the base and to maintain its length equal to

$$100 \quad \frac{1}{D} \sin. s$$

by a mechanism of the kind hereinafter described or by a cam, one or the other controlled in h and s automatically.

This arrangement also permits the gun to be directed at a distance on to an objective, from a lateral observation post in the following manner:

The gun receiving from the central post 110 the site and azimuth of the objective calculated from this post, the apparatus which forms the subject of the present invention, automatically converts these elements into site and azimuth appropriate to the gun, that is to say corrected of the effect of parallax 115 due to the distance between the lateral post and the gun, called the base.

This second use can be carried out in two ways; either the telescope itself of the aiming mechanism registers the data imparted from the post, and in such case, it is the gun which will be directed towards the target, or it is the gun which registers the data imparted from the post and it will be the telescope 120 which will be directed towards the target. This latter case is that where it is sought to take by the aiming telescope of the gun an objective chosen by the lateral post. 125

According to a feature of the invention, 130

the functioning of the apparatus as aiming apparatus or as corrector of parallax is effected by a single differential mechanism working according to the obvious formula:

$$\frac{t}{D} = \frac{t+k}{D} - \frac{k}{D}$$

where k is an arbitrary constant which depends only on the scales chosen.

- 10 In order to give at will to the vector PB a length $\frac{t}{D}$ or a length $\frac{1}{D}$ it will suffice therefore either to let the mechanisms function differentially, according to the above formula, or to suppress the part

$$\frac{t+k}{D}$$

- of this mechanism in such manner as to leave 20 in action only the part $\frac{k}{D}$

This manner of proceeding being very general the invention extends on this point to all mechanisms employing this splitting up 25 of $\frac{t}{D}$ in two differential movements and having for their object: the one to furnish the necessary data for the aiming of pieces against an aerial objective and the other the necessary data for the correction of paral- 30 laxies as well as the easy and rapid transition from the one to the other of these methods of functioning.

The part

$$\frac{t+k}{D}$$

will be carried out by a cam actuated at h and s , quite similar to that which has been 40 previously provided for $\frac{t}{D}$ as there is obviously also:

$$\frac{t+k}{D} = f(h, s).$$

45 The part $\frac{k}{D}$ would equally be able to be carried out by cam motion actuated at h and s .

Fig. 2 illustrates a mechanism enabling on the aiming apparatus a length to ma-

50 terialize equal to $\frac{\sin.s}{h}$ that is to say to $\frac{1}{D}$.

An arm OB is connected to the movement in site of the arm PCC' of Fig. 1. Its rotation about the axis O will therefore be 55 equal to s .

On this arm is mounted a screw V , actuated by gearing $e_1 e_2$ one of which is driven by a spindle extending along the axis of rotation of the arm OB , in such manner as to be capable of being actuated even during rotation of such arm.

A nut E on the screw V provided with a 65 roller G is fixed at a distance $OAA = \frac{1}{h}$.

On the roller G bears a straight ledge $a a'$ of a sliding plate C , constrained by guides to be displaced perpendicularly to $a a'$. It is seen that if by construction $a a'$ passes through o to the zero site, the displacement 70 of the slide C will be equal to:

$$\frac{\sin.s}{h} = \frac{1}{D}.$$

Fig. 3 illustrates the entire aiming ap- 75 paratus.

$P^1 C^1$ is the arm fast in site with the displacements of the gun. It turns about the horizontal axis $P^1 X$ under the action of a toothed wheel R , fast with this arm and which gears with a worm V_1 moved by hand by the handwheel V . On the same shaft $P^1 X$ is keyed the pinion V_4 which gears with the rack C_9 fast with the barrel, and produces the displacements of this latter ac- 80 cording to the sites.

On the arm is a screw V_2 actuated by gearing $e_1 e_2$. The shaft of e_2 extends through that of the arm $P^1 C^1$ in such manner as to be able to be actuated from a fixed point, outside the arm. The pitch of the screw V_2 is selected sufficiently small for the error introduced by the rotation of the arm, in the drive of screw to be quite negligible. (The same result could otherwise be obtained by driving the screw V_2 through the medium of a differential.)

On the screw V_2 is mounted a nut C^1 carrying a horizontal rod $C^1 C$ parallel to $P^1 X$ and terminating in an eye C or the equivalent.

Through this eye slides a rod CB controlling a telescope L , preferably elbowed, the optical axis of which is parallel to BC .

The point B is situated by construction in the horizontal plane passing through P^1 .

The telescope L is mounted on a horizontal shaft BL perpendicular to BC and turning in a support S itself capable of turning about a vertical axis $y^1 y$.

The telescope can therefore be directed in all directions. Graduations, not shown, will enable the value of the rotations of the telescope about its two axes to be read, which rotations are none other than the site and azimuth of the position of the objective at the moment of sighting (Ao of Fig. 1).

The support S is fixed on a slide C_1 constrained by a straight guide $Z Z'$ to be displaceable above a casing D pivoted about the vertical axis PY . The slide is displaceable horizontally in such manner that the path of $y^1 y$ passes through the axis PY and it is returned by a spring R_1 .

The axis PY is situated on the prolongation of the axis PX in the vertical plane which passes through the centre of the eye C and which is parallel to the arm $P^1 C^1$.

It is seen that if to P^1C^1 the value $\frac{1}{V}$ is given, and to PB the length

$$5 \quad \frac{t+k}{D} - \frac{k}{D},$$

and the casing D is turned so that PB remains parallel with the path of the target, 0 the triangle of Fig. 1 will have reconstituted in PBC .

It will suffice to direct the telescope on the target for P^1C^1 , that is to say the gun, to be directed on the position of the objective at 5 the arrival of the projectile, leaving at such instant.

Now, if to P^1C^1 the value $\frac{1}{(11)}$ is given, and

0 to PB the value $\frac{k}{D}$, and this latter is directed parallel to the base, if the site and the azimuth from the central post be reproduced either at the telescope or at the gun, the gun or the telescope will be directed on the target 5 sighted by the central post.

In order that the directing of PB may be maintained, the casing D is connected by a ring of teeth C_2 and by gearing C_3C_4 to a ring of teeth C_5 fast with the fixed portion of 0 the gun mounting. The casing obviously being fixed to the movable portion of this mounting, it will be easy to select the character and arrangement of the said gearing to ensure that during the rotation the vector 5 PB preserves a fixed direction in space.

To be able moreover to secure this vector initially in a position parallel to the path or to the base, the gear C_3 may be mounted free on the shaft of the gear C_4 . This latter may 0 carry at its end a crank M provided with a spring stud r adapted to enter holes formed in the gear C_3 .

On disengaging the stud from the holes, the casing D can be directed by hand and 5 in consequence the vector PB at will; then on letting the stud redescend into engagement with the holes, the casing D will be connected to the azimuth movement.

It remains to give to PB the lengths

$$0 \quad \frac{tk}{D} - \frac{k}{D} \text{ or } \frac{k}{D}$$

at will.

5 For this purpose the slide C_1 is formed with a rack and actuated by a gear E . This latter is itself actuated by a rack cut in the rod T_1 which extends along the vertical axis of the casing D .

0 The rod T_1 is spigotted at the point J into a second rod T_2 which extends it.

In this manner, the rod T_1 can turn with the casing D , whereas the rod T_2 does not participate in this rotation.

5 The rod T_2 carries at its end a small cylin-

drical gear e pivoted thereon, and which gears differentially with two racks C_6 and C_7 .

The rack C_6 is cut in a slide C_8 , similar to that of Fig. 2, which is actuated in site by the arm OAA connected by gearing $e_3 e_4$ to the site screw V_1 .

OAA is maintained equal to $\frac{1}{h}$ as has been seen previously (Fig. 2).

The slide C_8 has therefore a movement 75 equal to

$$\frac{k \sin. s}{h} \text{ or } \frac{k}{D},$$

parallel to PY .

The rack C_7 is cut in a rod parallel to PY formed in two pieces T_3, T_4 screwed together.

A stud F prevents by being appropriately guided the piece T_3 turning and abuts at H at the bottom of the downward stroke thereof.

The rod T_4 bears at its lower end on a cam K actuated mechanically as regards site s and as regards altitude h in the following 90 manner:

On the shaft G of the cam K is keyed a wheel R_2 gearing with a worm V_5 . This worm V_5 is fast with the driving mechanism of the barrel as regards site through the medium of bevel wheels $e_7 e_8$. However, this shaft G of the cam may have a threaded portion (not clearly shown) which may be screwed to the frame in order to support the shaft. On this shaft is keyed a pinion e_{10} in engagement with a pinion e_9 fast with a driving rod T_5 actuated by a crank M_2 . This rod T_5 itself has a screw threaded portion on which becomes displaced by the rotation of the rod T_5 a rider I , the displacements of which are measured on a scale G_2 graduated in altitudes.

The cam K has a surface such as to impart to T_4 a displacement equal to:

$$110 \quad \frac{t+k}{D} = f(h, s).$$

The spindle T_4 carries a collar e_5 cut as a cylindrical gear, in engagement with a gear e_6 with long teeth, whatever be the position of the rod T_4 .

The gear e_6 can be moved by hand by the crank M_1 .

This gear, by virtue of a mechanical connection to a suitable movable member provided with abutments and not illustrated being actuated fully in a given direction unscrews the rod T_4 on the rod T_3 so far as to impart to these rods a fixed total length corresponding to the correct functioning of the cam K .

In this position, this latter gives

$$\frac{t+k}{D}$$

whereas the slide gives $\frac{k}{D}$. These movements act differentially on the roller e which transmits to the slide C_1 a displacement proportional to:

$$\frac{(t+k)}{D} - \frac{k}{D} = \frac{t}{D}.$$

10 The apparatus then acts as an aiming apparatus.

When the handwheel M_1 is fully turned in the inverse direction, the stud F comes finally to abut against H by virtue of the returning effort exerted by the spring R_1 and the rod T_4 screwing entirely on the rod T_3 reascends so far as completely to escape the action of the cam K .

15 The action of this latter is thus annulled and the slide C_1 only receives the displacement of the slide C_8 , that is to say proportional to $\frac{k}{D}$.

20 The apparatus is then in the condition to operate to correct parallaxes.

25 It is to be noted that the transition from the one to the other of these modes of operating is effected as progressively as desired and without any shock on the aiming.

30 Fig. 4 shows the mounting of the aiming contrivance on the gun. It is clearly seen from Fig. 4 that the entire contrivance is mounted on the pivoting portion W_1 of the gun mounting, the axis of rotation being $Z Z^1$. In this figure can easily be seen the exposed members of the aiming contrivance as regards direction constituted by a handwheel W_2 driving a pinion W_3 in engagement with a circular rack C_5 fixed on the base and 35 concentric with the axis $Z Z^1$. This figure also shows that the sole connection between the aiming mechanism which forms the subject of the invention and the movement as regards azimuth of the gun is constituted by the gear C_4 in engagement with the circular rack C_5 and keyed on the shaft of the crank M . As has been demonstrated above this 40 connection enables by virtue of the gears C_2 , C_3 , C_4 the constant maintenance of the direction of the casing D , notwithstanding the rotation of the platform W_1 about the axis $Z Z^1$ that is to say the preservation on the aiming apparatus, notwithstanding the displacements of this latter, of the direction of the 45 path of the objective.

50 I claim:

1. In a gun for firing a projectile at a moving aerial objective situated at a distance D from the gun and being displaced at a constant velocity V in a straight line, a fixed gun mounting, a frame mounted on this mounting, means enabling displacement of the frame on the mounting in the direction of azimuths, a barrel mounted on this frame, 55 means enabling displacement of the barrel

on the frame in the direction of sites, an aiming apparatus mounted on this frame, a telescope movable in all directions mounted on this aiming apparatus and directed towards the objective, mechanical movement transmission means interposed between the telescope and the site displacement mechanism of the barrel, correction means mounted in the aiming apparatus and modifying the effect of these transmission means according to the characteristics of the displacement of the objective, these correction means being constituted by movable members effecting in the aiming apparatus the reproduction on the scale $\frac{1}{VD}$ of the triangle formed by the gun, 70 the position of the objective on the departure of the projectile, the position of the objective on the arrival of the projectile, which enables the values of the site and azimuth of the position which the objective will occupy on the arrival of the projectile to be imparted to the site and azimuth of the gun.

2. In a gun for firing a projectile at a moving aerial objective situated at a distance D 75 from the gun and being displaced at a constant velocity V in a straight line, a fixed gun mounting, a frame mounted on this mounting, means enabling displacement of the frame on the mounting in the direction of azimuths, a barrel mounted on this frame, means enabling displacement of the barrel on the frame in the direction of sites, an aiming apparatus mounted on this frame, a telescope movable in all directions mounted on this aiming apparatus and directed towards the objective, mechanical movement transmission means interposed between the telescope and the site displacement mechanism of the barrel, correction means mounted in the aiming apparatus and modifying the effect of these transmission means according to the characteristics of the displacement of the objective, these correction means being constituted by movable members effecting in the aiming apparatus the reproduction on the scale $\frac{1}{VD}$ of the triangle formed by the gun, the position of the objective on the departure of the projectile, the position of the objective on the arrival of the projectile, continuous mechanical connections between these movable members and the means enabling the displacement of the barrel on the frame, which enables the values of the site and azimuth of the position which the objective will occupy on the arrival of the projectile to be imparted to the site and azimuth of the gun.

3. In a gun for firing a projectile at a moving aerial objective situated at a distance D from the gun and being displaced at a constant velocity V in a straight line, a fixed gun mounting, a frame mounted on this mounting, means enabling displacements of the frame on the mounting in the direction of

azimuths, a barrel mounted on this frame, means enabling displacements of the barrel on the frame in the direction of sites, an aiming apparatus mounted on this frame and comprising a tangent screw (V_1) driven by these displacement means of the barrel in the direction of the sites, a helicoidal wheel (R) in engagement with this tangent screw, a bearing frame fast with this helicoidal wheel (R), a screw (V_2) mounted in these bearings, means ($e_1 e_2$) of driving this screw (V_2) independent of the bearing frame, a slide (c^1) screwed on this screw (V_2), means for maintaining this slide against any rotation, driving means (c) mounted on this slide, a telescope movable in all directions mounted on the frame and fast in the direction of the sites of these driving means, correction means mounted on the frame and modifying the effect of these driving means according to the characteristics of the displacement of the objective, which enables the values of the site and azimuth of the position which the objective will occupy on the arrival of the projectile to be imparted to the site and azimuth of the gun.

4. In a gun for firing a projectile at a moving aerial objective situated at a distance D from the gun and being displaced at a constant velocity V in a straight line the projectile making a flight of a duration t , a fixed gun mounting, a frame mounted on this mounting, means enabling displacements of the frame on the mounting in the direction of azimuths, a barrel mounted on this frame, means enabling displacements of the barrel on the frame in the direction of sites, an aiming apparatus mounted on this frame and comprising a tangent screw (V_1) driven by these displacement means of the barrel in the direction of the sites, a helicoidal wheel (R) in engagement with this tangent screw, a bearing frame fast with this helicoidal wheel (R), a screw (V_2) mounted in these bearings, means ($e_1 e_2$) of driving this screw (V_2) independent of the bearing frame, a slide (c^1) screwed on this screw (V_2), means for maintaining this slide against any rotation, driving means (c) mounted on this slide, a telescope movable in all directions mounted on the frame and fast in the direction of the sites of these driving means, means mounted on this frame for guiding this telescope in a horizontal direction parallel to the displacement of the objective, correction means effecting the displacement of this telescope in this direction by an amount equal to $\frac{t}{D}$, these correction means being

constituted by a support (C_1) displaced in the guide means and fast with the telescope for the horizontal displacements, continuous mechanical connections connecting this support (C_1) to a slide (C_s) sliding on the frame, a rolling track carried by this slide (C_s) and directed perpendicularly to the direction of displacement of the slide, a roller (G) rolling on the rolling track, a nut fast with this roller, a screw screwed in this nut, a bearing support supporting this screw and pivoted on the frame, continuous mechanical connections between this support and the means enabling the displacement of the barrel in the direction of the sites, driving means of the screw independent of the frame for the displacement of the nut by an amount $\frac{1}{h}$, which enables the values of the site and azimuth of the position which the objective will occupy on the arrival of the projectile to be imparted to the site and azimuth of the gun.

6. In a gun for firing a projectile at a moving aerial objective situated at a distance D from the gun and being displaced at a constant velocity V in a straight line the projectile making a flight of a duration t , a fixed gun mounting, a frame mounted on this mounting, means enabling displacements of the frame on the mounting in the direction of azimuths, a barrel mounted on this frame, means enabling displacements of the barrel

130

- on the frame in the direction of sites, an aiming apparatus mounted on this frame and comprising a tangent screw (V_1) driven by these displacement means of the barrel in 5 the direction of the sites, a helicoidal wheel (R) in engagement with this tangent screw, a bearing frame fast with this helicoidal wheel (R), a screw (V_2) mounted in these bearings, means ($e_1 e_2$) of driving this screw 10 (V_2) independent of the bearing frame, a slide (c^1) screwed on this screw (V_2), means for maintaining this slide against any rotation, driving means (c) mounted on this slide, a telescope movable in all directions mounted 15 on the frame and fast in the direction of the sites of these driving means, means mounted on this frame for guiding this telescope in a horizontal direction parallel to the displacement of the objective, gearing interposed 20 between these guiding means and the gun mounting and enabling the direction of these guiding means to be maintained invariable notwithstanding the displacement of the frame on the mounting, correction means effecting the displacement of this telescope in 25 this direction by an amount equal to $\frac{t}{D}$ which enables the values of the site and azimuth of the position which the objective will occupy 30 on the arrival of the projectile to be imparted to the site and azimuth of the gun.
7. In a gun for firing a projectile at a moving aerial objective situated at a distance D from the gun and being displaced at a constant velocity V in a straight line the projectile making a flight of a duration t , a fixed gun mounting, a frame mounted on this mounting, means enabling displacements of the frame on the mounting in the direction of 35 azimuths, a barrel mounted on this frame, means enabling displacements of the barrel on the frame in the direction of sites, an aiming apparatus mounted on this frame and comprising a tangent screw (V_1) driven by 40 these displacement means of the barrel in the direction of the sites, a helicoidal wheel (R) in engagement with this tangent screw, a bearing frame fast with this helicoidal wheel (R), a screw (V_2) mounted in these 45 bearings, means ($e_1 e_2$) of driving this screw (V_2) independent of the bearing frame, a slide (c^1) screwed on this screw (V_2), means for maintaining this slide against any rotation, driving means (c) mounted on this slide, 50 a telescope movable in all directions mounted on the frame and fast in the direction of the sites of these driving means, means mounted on this frame for guiding this telescope in a horizontal direction parallel to the displacement 55 of the objective, gearing interposed between these guiding means and the gun mounting and enabling the direction of these guiding means to be maintained invariable notwithstanding the displacement of the frame on the mounting, a crank (M) fast with 60 this gearing, a stud (r) movable on this crank and coming into engagement at will with the guide means for instantaneous disconnection of the control between the guide means and the gun mounting, correction means effecting the displacement of this telescope in 65 this direction by an amount equal to $\frac{t}{D}$ which enables the values of the site and azimuth of the position which the objective will occupy on the arrival of the projectile to be imparted to the site and azimuth of the gun. 70
8. In a gun for firing a projectile at a moving aerial objective situated at a distance D from the gun and being displaced at a constant velocity V in a straight line the projectile making a flight of a duration t , the fire being controlled by an observer situated at a distance l from the gun, a fixed gun mounting, a frame mounted on this mounting, means enabling displacements of the frame on the mounting in the direction of azimuths, a barrel mounted on this frame, means enabling displacements of the barrel on the frame in the direction of sites, an aiming apparatus mounted on this frame, a telescope movable in all directions mounted in this aiming apparatus and directed towards the objective, mechanical movement transmission means interposed between the telescope and the site displacement mechanism of the barrel, correction means mounted in the aiming apparatus and modifying the effect of these transmission means according to the characteristics of the displacement of the objective, means for converting sites and azimuths imparted by the observer into sites and azimuths utilizable at the gun, these converting means being constituted by movable members effecting on the aiming apparatus 85 the reproduction on the scale $\frac{1}{1D}$ of the triangle formed by the gun, the observation post and the objective, which enables the values of the site and azimuth of the position which the objective will occupy on the arrival of the projectile to be imparted to the site and azimuth of the gun. 90
9. In a gun for firing a projectile at a moving aerial objective situated at a distance D from the gun and being displaced at a constant velocity V in a straight line the projectile making a flight of a duration t , the fire being controlled by an observer situated at a distance l from the gun, a fixed gun mounting, a frame mounted on this mounting, means enabling displacements of the frame on the mounting in the direction of azimuths, a barrel mounted on this frame, means enabling displacements of the barrel on the frame in the direction of sites, an aiming apparatus mounted on the frame and comprising a tangent screw (V_1) driven by these displacement means of the tube in the direction of 100 105 110 115 120 125 130

sites, a helicoidal wheel (R) in engagement with this tangent screw, a bearing frame fast with this helicoidal wheel (R), a screw (V₂) mounted in these bearings, means (e₁ e₂) of driving this screw (V₂) independent of the bearing frame, a slide (c¹) screwed on this screw (V₂), means for maintaining this slide against any rotation, driving means (c) mounted on this slide, a telescope movable in all directions mounted on the frame and fast in the direction of sites of these driving means, means mounted on the frame for guiding this telescope in a horizontal direction parallel with the displacement of the objective, correction means effecting the displacement of this telescope in this direction by an amount equal to $\frac{t}{D}$, a slide mechanism actuated by the displacing means of the barrel on the frame effecting the displacement of the telescope by an amount equal to $\frac{k}{D}$, a cam (K) mounted on an axis of the frame, means effecting rotation of the cam (K) about its axis according to the site (s) of the objective, means effecting the translation of this cam (K) on its axis according to the altitude (h) of the objective, this cam by itself alone communicating to the telescope displacements equal to

$$\frac{t+k}{D},$$

a differential mechanism interposed between the cam, the slide mechanism and the telescope, communicating to this latter a displacement equal to

$$\frac{t+k}{D} - \frac{k}{D} = \frac{t}{D},$$

which enables the values of the site and azimuth of the position which the objective will occupy on the arrival of the projectile to be imparted to the site and azimuth of the gun.

10. In a gun for firing a projectile at a moving aerial objective situated at a distance D from the gun and being displaced at a constant velocity V in a straight line the projectile making a flight of a duration t, the fire being controlled by an observer situated at a distance l from the gun, a fixed gun mounting, a frame mounted on this mounting, means enabling displacements of the frame on the mounting in the direction of azimuths, a barrel mounted on this frame, means enabling displacements of the barrel on the frame in the direction of sites, an aiming apparatus mounted on the frame and comprising a tangent screw (V₁) driven by these displacement means of the tube in the direction of sites, a helicoidal wheel (R) in engagement with this tangent screw, a bearing frame fast with this helicoidal wheel (R), a screw (V₂) mounted in these bear-

ings, means (e₁ e₂) of driving this screw (V₂) independent of the bearing frame, a slide (c¹) screwed on this screw (V₂), means for maintaining this slide against any rotation, driving means (c) mounted on this slide, a telescope movable in all directions mounted on the frame and fast in the direction of sites of these driving means, means mounted on the frame for guiding this telescope in a horizontal direction parallel with the displacement of the objective, correction means effecting the displacement of this telescope in this direction by an amount equal to $\frac{t}{D}$, a slide mechanism actuated by the displacing means of the barrel on the frame effecting the displacement of the telescope by an amount equal to $\frac{k}{D}$ a cam (K) mounted on an axis of the frame, means effecting rotation of the cam (K) about its axis according to the site (s) of the objective, means effecting the translation of this cam (K) on its axis according to the altitude (h) of the objective, this cam by itself alone communicating to the telescope displacements equal to

$$\frac{t+k}{D},$$

a differential mechanism interposed between the cam, the slide mechanism and the telescope, communicating to this latter a displacement equal to

$$\frac{t+k}{D} - \frac{k}{D} = \frac{t}{D},$$

means (M₁ e₅ e₆) enabling disconnection of the telescope from the cam and leaving in action only the mechanism effecting the dis-

placement $\frac{k}{D}$ and employing the aiming apparatus as corrector of parallax, which enables the values of the site and azimuth of the position which the objective will occupy on the arrival of the projectile to be imparted to the site and azimuth of the gun.

In testimony whereof I have signed this specification.

RENÉ RIBEROLLES.
